UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,425,993.

Specification of Letters Patent. Patented Aug. 15, 1922.

Continuation of application Serial No. 309,710, filed July 9, 1919. This application filed August 5, 1920, Serial No. 401,431. Renewed February 27, 1922. Serial No. 539,766.

To all whom it may concern:

Be it known that I, RONALD A. McCANN, a citizen of the United States, residing at Swissvale, in the county of Allegheny and 5 State of Pennsylvania, have invented certain new and useful Improvements in Railway-Traffic-Controlling Apparatus, of which the following is a specification.

My invention relates to railway traffic 10 controlling systems, and particularly to systems of the type comprising ramps located at intervals in the trackway and each arranged to co-operate with train carried governing apparatus to give a proceed or a stop indication aboard the train according as the ramp 15 is energized or de-energized. More specifically, my invention relates to trackway apparatus for systems of this character suitable for use on single track over which 20 traffic moves in both directions.

The present application is a continuation 25 of my copending application filed July 9, 1919, Serial No. 309,710, for railway traffic controlling apparatus, in so far as the subject matter common to the two is concerned.

One object of my invention is the control 30 of the ramps in such manner that, except for certain conditions existing in the neighborhood of passing sidings, two trains moving towards each other will be kept a greater distance apart than two trains moving in the same direction.

I will describe one form of trackway apparatus embodying my invention, and will 35 then point out the novel features thereof in claims.

In the accompanying drawings, Figs. 1, 2, 40 3 and 4 are diagrammatic views showing one form of trackway apparatus embodying my invention, it being understood that a complete system is formed by placing these views together end to end in the order named. Fig. 5 is a view showing the control limits of the signals and ramps shown 45 in Figs. 1 to 4.

Referring now to Figs. 1 to 4 of the drawings, the reference characters 2 and 2^a designate the track rails of a single track over which traffic moves in both directions. The 50 stretch of track here shown includes two passing sidings A and B. The rails are divided by insulated joints 3 into a plurality of track sections 4—5, 5—6, * * * 27—28, and each section is provided with a

track circuit comprising a track battery *b*, 55 the rails of the section, and a track relay designated by the reference character *T* with a suitable exponent.

Traffic along the stretch from west to east is governed by a plurality of roadside signals *S'*, *S²*, * * * *S¹⁵*, while traffic along the stretch from east to west is governed by a plurality of signals *S²*, *S⁴*, * * * *S¹⁶*. As here shown, each signal is located adjacent the junction of two track sections, 65 although this exact location is not essential. The control of these signals will be explained hereinafter.

Each signal is provided with a ramp which is designated by the reference character *R* 70 with the same exponent as that of the corresponding signal. Each ramp is located on the same side of the track as the corresponding signal; that is, all of the ramps which control eastbound trains are shown below 75 the track in the drawing, and all of the ramps which control westbound trains are shown above the track. Each ramp is located a short distance in advance of its signal, and as here shown, the ramps are arranged in pairs, each pair comprising an eastbound and a westbound ramp; this particular disposition of the ramps, however, is 80 not essential to my invention.

It is understood that each car or train 85 which passes along the track is equipped with apparatus which co-operates with the ramps corresponding to the direction in which the car or train is moving, and which causes, at each ramp, a proceed or a stop 90 indication aboard the train according as the ramp is energized or de-energized. This indication may be given by means of visual signals on the train, or it may be given by apparatus which controls the brakes of the 95 train; in the latter case a stop indication (a de-energized ramp) means an automatic application of the brakes, and a proceed indication (an energized ramp) means that such automatic application does not occur. 100 Various forms of train carried apparatus which will co-operate with the ramps in the manner set forth are known in the art, and inasmuch as this apparatus forms no part of my present invention it is not illustrated 105 herein.

Each signal *S* is controlled by a line relay which is designated by the reference char-

acter A with the same exponent as that of the signal which it controls.

Each signal is provided with a caution circuit and a proceed circuit. Referring 5 particularly to signal S⁵, the caution circuit is from battery B⁵, through wires 30 and 31, front point of contact 32 of line relay A⁵, wire 33, operating mechanism of signal S⁵, wire 34, front point of contact 35, 10 wires 36, 37 and 91 to battery B⁵. The proceed circuit is from battery B⁵, through wires 30 and 31, contact 32, wire 38, polarized contact 39 of relay A⁵, wire 40, and thence as before to battery B⁵. It will be 15 seen that this proceed circuit is closed only when relay A⁵ is energized in such direction as to close contact 39, which direction I will term the "normal" energization of this relay, as distinguished from the "reverse" 20 direction of energization wherein the signal indicates caution.

The control circuits for each of the signals are similar to those for signal S⁵, and hence they need not be traced in detail herein.

25 The control of the line relays A will be explained hereinafter.

The supply of current to each ramp R is controlled by a ramp relay which is designated by the reference character C with the same exponent as that of the corresponding ramp and signal. Considering ramp R⁵, for example, the energizing circuit is from battery B⁵, through wires 30 and 41, contact 42, wire 43, ramp R⁵, thence through the train carried apparatus when a train is over the ramp, to rail 2^a, then through wires 44, 156, 37, and 91, to battery B⁵. Ramp R⁵ is energized, then, only when relay C⁵ is closed.

40 Relay C⁵ is provided with a pick-up circuit which passes from battery B⁵, through wire 30, contact 45 operated by signal S⁵, wire 46, back contact 47 of track relay T¹⁰, wires 48 and 49, winding of relay C⁵, and
45 wires 50 and 91 to battery B⁵. It will be

seen that this circuit is closed only when track relay T^{10} is de-energized and signal S^5 is in the proceed or caution position or somewhere between these two positions.

50 Relay C⁵ can be picked up then only when a car or train enters track section 10-11 moving toward the east; when a westbound train passes along the track it places signal S⁵ in the stop position before reaching

55 S. in the stop position before reaching point 11 as will appear hereinafter, and, consequently, when this train opens track relay T^{10} , the pick-up circuit for relay C^5 is opened at contact 45, so that the relay remains deenergized. Relay C^5 is provided

60 with a holding or stick circuit which passes from battery B^5 , through wires 30 and 82, back contact 51 of relay T^{11} , wire 52, contact 53 of relay C^6 , wires 54 and 49, winding of relay C^6 , and wires 50 and 91 to battery B^5 . It will be seen, therefore, that

when the relay C⁵ has been picked up by an eastbound train in section 10-11, this relay remains closed as long as track relay T¹¹ is de-energized, that is, as long as any part of the train is in section 11-12, so that ramp R⁵ remains energized until the rear of the train passes point 12. The reason for this stick control of relay C⁵ is to keep the ramp R⁵ energized as long as any part of the car or train is passing over this ramp. 75 70

The control of each ramp R by the corresponding ramp relay is the same as the control just explained for ramp R⁵. The pick-up and stick circuits for each ramp relay C, except the stick circuits for relays C², C³, C⁶, C⁷, C¹⁰, C¹¹, C¹⁴ and C¹⁵, are the same as those just traced for relay C³. Considering ramp relay C³ as an example of this group, the stick circuit includes a back contact 105 of a relay D³, which relay is merely a repeater for track relay T³. The circuit for relay D³ is from battery B³, through wires 55 and 101, winding of relay D³, wire 102, contact 103 of track relay T³, and wire 104 to battery B³. The reason for the insertion of this relay D³ is that there is no track relay for section 8-9 at signal S³. Each other relay D is provided with a similar circuit.

The line relay A' is provided with a circuit which passes from battery B³, through wire 55, pole-changer P³ operated by signal S³, wire 56, contact 57 of track relay T⁹, wire 58, contact 59 of track relay T¹⁰, wires 60 and 61, contact 62 of track relay T¹¹, wire 63, contact 64 of track relay T¹², wire 65, common wire O, wire 66 (adjacent signal S'), wire 67, winding of relay A', wire 68, contact 69 of track relay T⁵, wire 70, contact 71 of track relay T⁶, wire 72, contact 73, of track relay T⁷, wire 74, contact 75 of relay D³, wire 76, pole-changer P³, and wire 77 to battery B³. So far as this circuit is concerned, then, it will be noted that relay A' is controlled by all of the track relays for the sections between points 5 and 13, so that signal S' would be held in the stop position by a train at any place on the track between these two points regardless of the direction in which such train is moving. This is indicated in Fig. 5 by the solid and dash control line leading from signal S'. The circuit for relay A' is provided, however, with a shunt around the contacts of track relays T¹¹ and T¹², which shunt passes from wire 60, through wire 78, contact 79 of an auxiliary relay X⁵, and wires 80 and 81, to the common wire O. Auxiliary relay X⁵ is provided with a pick-up circuit which passes from battery B⁵, through wire 30, wire 41, contact 200 of relay C⁵, wires 83 and 84, winding of relay X⁵, wire 85, back contact 86 of relay A⁵, and wires 87, 37 and 91 to battery B⁵. This pick-up circuit can be closed, then, only when ramp relay C⁵ is 130

closed and line relay A^5 is open; and since ramp relay C^5 is closed only by an eastbound train, and since relay A^5 does not open until such a train passes point 11, it follows that relay X^5 can be closed only when an eastbound train passes point 11. Relay X^5 is provided with a holding circuit which passes from battery B^5 , through wires 30 and 88, contact 89 of relay X^5 , wires 90 and 84, winding of relay X^5 , wire 85, back contact 86 of relay A^5 , and wires 87, 37, and 91 to battery B^5 . When relay X^5 has been closed, then, it will remain closed as long as line relay A^5 remains open.

15 It will be seen from the foregoing that when a train moving toward the east passes point 11, the circuit for line relay A' becomes closed whereupon signal S' will move to the caution or to the proceed position depending upon the position of pole-changer P^3 . This is indicated in Fig. 5 by the solid portion of the control line leading from signal S' . Pole-changer P^3 is in such position as to energize relay A' in the normal 20 direction when signal S^3 indicates caution or proceed, and in the reverse direction when the signal S^3 indicates stop.

25 Inasmuch as the ramp relay C' can become closed only when signal S' is in the caution or proceed position, that is, only when line relay A' is energized, it follows that ramp R' is held in the de-energized condition by an eastbound train until the rear end of such train has passed point 11, whereas when a westbound train passes along the track, this ramp cannot become energized after the front end of such train has passed point 13. In other words, the control limits for ramp R' are the same as 30 those for signal S' , and so they are as indicated by the control line for signal S' in Fig. 5.

35 To express the foregoing in another way, signal S' is held at stop and ramp R' is held de-energized by an eastbound train up to point 11, and by a westbound train from point 13.

40 An auxiliary relay similar to X^5 is provided for each of the following signals: S^2 , S^3 , S^5 , S^8 , S^{10} , S^{11} , S^{12} , and S^{16} . The circuits for auxiliary relays X^8 , X^{13} , and X^{16} , are similar to those traced hereinbefore for relay X^5 . The stick circuits for relays X^2 , X^3 , X^{10} and X^{11} , however, are controlled by 45 back contacts of the corresponding D relays, for the reason that there is no track relay adjacent each of these X relays, but in other respects these circuits are the same as the circuits for relay X^5 .

50 The line relay A^9 which controls signal S^9 and ramp R^9 is governed in exactly the same way as line relay A' ; that is, line relay A^9 is controlled by contact 92 of relay T^{17} , contact 93 of relay T^{18} , contact 94 of relay T^{19} , contact 95 of relay D^{11} , contact 96 of

relay T^{21} , contact 97 of relay T^{22} , contact 98 of relay T^{23} , and contact 99 of relay T^{24} . This circuit is also controlled by pole-changer P^{11} operated by signal S^{11} , and it is provided with a shunt around contacts 98 and 99, which shunt is controlled by contact 100 of auxiliary relay X^{13} . It follows, then, that signal S^9 and ramp R^9 are controlled up to point 23 for eastbound movements, and up to point 25 for westbound movements, as indicated in Fig. 5.

The circuit for line relay A^7 , which controls signal S^7 , is from battery B^9 , through wire 106, pole-changer P^9 , wire 107, contact 108 of track relay T^{18} , wire 109, contact 110 of track relay T^{19} , wires 111 and 112, contact 113 of relay D^{11} , wire 114, contact 115 of track relay T^{21} , wire 116, contact 117 of track relay T^{22} , wire 118, contact 119 of relay D^{14} , wire 120, contact 121 of track relay T^{24} , wire 122, common wire O, wires 123 and 124, (adjacent signal S^7), winding of relay A^7 , wire 125, contact 126 of relay D^7 , wire 127, back contact 128 of relay X^8 , wire 129, contact 129^a of track relay T^{15} , wire 130, contact 131 of track relay T^{16} , wire 132, contact 133 of relay T^{17} , wire 134, pole-changer P^9 , and wire 106^a to battery B^9 . This circuit is provided with a shunt around the contacts of relays D^{11} , T^{21} , T^{22} , T^{24} and D^{14} , which shunt is from wire 111, through wire 135, contact 136 of relay X^{11} , and wires 137 and 138, to common wire O. It will be seen, therefore, that while an eastbound train is passing along the track, signal S^7 is held at stop and ramp R^7 is kept de-energized until the train passes signal S^{11} (that is, point 20); but that when a westbound train passes along the track, signal S^7 is placed at stop when the train passes point 25 and ramp R^7 is kept de-energized from the time a train passes this latter point until it passes signal S^7 . These control limits are indicated more clearly in Fig. 5.

The circuit for line relay A^5 is from battery B^7 through wire 139, pole-changer P^7 , wire 140, contact 141 of relay T^{15} , wire 142, contact 143 of relay T^{16} , wire 144^a, contact 175 of track relay T^{17} , wire 144, common wire O, wires 81 and 145, winding of relay A^5 , wire 146, contact 147 of track relay T^{11} , wire 148, contact 149 of relay T^{12} , wire 150, contact 151 of relay T^{13} , wire 152, contact 153 of relay D^7 , wire 154, pole-changer P^7 , and wire 155 to battery B^7 . It will be seen, therefore, that signal S^5 and ramp R^5 are controlled up to signal S^{10} , that is, up to point 18, by train movements in both directions. This is shown more clearly in Fig. 5.

The circuit for relay A^3 is from battery B^5 , through wires 91, 37 and 156, pole-changer P^5 , wire 157, contact 158 of track relay T^{12} , wire 65, common wire O, wire 159, (adjacent signal S^3) winding of relay A^3 , wire 160, contact 161 of relay T^8 , wire 162, contact 163 of relay T^{13} , wire 164, contact 165 of relay T^{14} , wire 166, contact 167 of relay T^{15} , wire 168, contact 169 of relay T^{16} , wire 170, contact 171 of relay T^{17} , wire 172, contact 173 of relay T^{18} , wire 174, contact 175 of relay T^{19} , wire 176, contact 177 of relay D^{11} , wire 178, contact 179 of relay D^{14} , wire 180, contact 181 of relay D^{17} , wire 182, contact 183 of relay D^{18} , wire 184, contact 185 of relay D^{19} , wire 186, contact 187 of relay D^{21} , wire 188, contact 189 of relay D^{22} , wire 190, contact 191 of relay D^{23} , wire 192, contact 193 of relay D^{24} , wire 194, contact 195 of relay D^{25} , wire 196, contact 197 of relay D^{26} , wire 198, contact 199 of relay D^{27} , wire 200, contact 201 of relay D^{28} , wire 202, contact 203 of relay D^{29} , wire 204, contact 205 of relay D^{30} , wire 206, contact 207 of relay D^{31} , wire 208, contact 209 of relay D^{32} , wire 210, contact 211 of relay D^{33} , wire 212, contact 213 of relay D^{34} , wire 214, contact 215 of relay D^{35} , wire 216, contact 217 of relay D^{36} , wire 218, contact 219 of relay D^{37} , wire 220, contact 221 of relay D^{38} , wire 222, contact 223 of relay D^{39} , wire 224, contact 225 of relay D^{40} , wire 226, contact 227 of relay D^{41} , wire 228, contact 229 of relay D^{42} , wire 230, contact 231 of relay D^{43} , wire 232, contact 233 of relay D^{44} , wire 234, contact 235 of relay D^{45} , wire 236, contact 237 of relay D^{46} , wire 238, contact 239 of relay D^{47} , wire 240, contact 241 of relay D^{48} , wire 242, contact 243 of relay D^{49} , wire 244, contact 245 of relay D^{50} , wire 246, contact 247 of relay D^{51} , wire 248, contact 249 of relay D^{52} , wire 250, contact 251 of relay D^{53} , wire 252, contact 253 of relay D^{54} , wire 254, contact 255 of relay D^{55} , wire 256, contact 257 of relay D^{56} , wire 258, contact 259 of relay D^{57} , wire 260, contact 261 of relay D^{58} , wire 262, contact 263 of relay D^{59} , wire 264, contact 265 of relay D^{60} , wire 266, contact 267 of relay D^{61} , wire 268, contact 269 of relay D^{62} , wire 270, contact 271 of relay D^{63} , wire 272, contact 273 of relay D^{64} , wire 274, contact 275 of relay D^{65} , wire 276, contact 277 of relay D^{66} , wire 278, contact 279 of relay D^{67} , wire 280, contact 281 of relay D^{68} , wire 282, contact 283 of relay D^{69} , wire 284, contact 285 of relay D^{70} , wire 286, contact 287 of relay D^{71} , wire 288, contact 289 of relay D^{72} , wire 290, contact 291 of relay D^{73} , wire 292, contact 293 of relay D^{74} , wire 294, contact 295 of relay D^{75} , wire 296, contact 297 of relay D^{76} , wire 298, contact 299 of relay D^{77} , wire 300, contact 301 of relay D^{78} , wire 302, contact 303 of relay D^{79} , wire 304, contact 305 of relay D^{80} , wire 306, contact 307 of relay D^{81} , wire 308, contact 309 of relay D^{82} , wire 310, contact 311 of relay D^{83} , wire 312, contact 313 of relay D^{84} , wire 314, contact 315 of relay D^{85} , wire 316, contact 317 of relay D^{86} , wire 318, contact 319 of relay D^{87} , wire 320, contact 321 of relay D^{88} , wire 322, contact 323 of relay D^{89} , wire 324, contact 325 of relay D^{90} , wire 326, contact 327 of relay D^{91} , wire 328, contact 329 of relay D^{92} , wire 330, contact 331 of relay D^{93} , wire 332, contact 333 of relay D^{94} , wire 334, contact 335 of relay D^{95} , wire 336, contact 337 of relay D^{96} , wire 338, contact 339 of relay D^{97} , wire 340, contact 341 of relay D^{98} , wire 342, contact 343 of relay D^{99} , wire 344, contact 345 of relay D^{100} , wire 346, contact 347 of relay D^{101} , wire 348, contact 349 of relay D^{102} , wire 350, contact 351 of relay D^{103} , wire 352, contact 353 of relay D^{104} , wire 354, contact 355 of relay D^{105} , wire 356, contact 357 of relay D^{106} , wire 358, contact 359 of relay D^{107} , wire 360, contact 361 of relay D^{108} , wire 362, contact 363 of relay D^{109} , wire 364, contact 365 of relay D^{110} , wire 366, contact 367 of relay D^{111} , wire 368, contact 369 of relay D^{112} , wire 370, contact 371 of relay D^{113} , wire 372, contact 373 of relay D^{114} , wire 374, contact 375 of relay D^{115} , wire 376, contact 377 of relay D^{116} , wire 378, contact 379 of relay D^{117} , wire 380, contact 381 of relay D^{118} , wire 382, contact 383 of relay D^{119} , wire 384, contact 385 of relay D^{120} , wire 386, contact 387 of relay D^{121} , wire 388, contact 389 of relay D^{122} , wire 390, contact 391 of relay D^{123} , wire 392, contact 393 of relay D^{124} , wire 394, contact 395 of relay D^{125} , wire 396, contact 397 of relay D^{126} , wire 398, contact 399 of relay D^{127} , wire 400, contact 401 of relay D^{128} , wire 402, contact 403 of relay D^{129} , wire 404, contact 405 of relay D^{130} , wire 406, contact 407 of relay D^{131} , wire 408, contact 409 of relay D^{132} , wire 410, contact 411 of relay D^{133} , wire 412, contact 413 of relay D^{134} , wire 414, contact 415 of relay D^{135} , wire 416, contact 417 of relay D^{136} , wire 418, contact 419 of relay D^{137} , wire 420, contact 421 of relay D^{138} , wire 422, contact 423 of relay D^{139} , wire 424, contact 425 of relay D^{140} , wire 426, contact 427 of relay D^{141} , wire 428, contact 429 of relay D^{142} , wire 430, contact 431 of relay D^{143} , wire 432, contact 433 of relay D^{144} , wire 434, contact 435 of relay D^{145} , wire 436, contact 437 of relay D^{146} , wire 438, contact 439 of relay D^{147} , wire 440, contact 441 of relay D^{148} , wire 442, contact 443 of relay D^{149} , wire 444, contact 445 of relay D^{150} , wire 446, contact 447 of relay D^{151} , wire 448, contact 449 of relay D^{152} , wire 450, contact 451 of relay D^{153} , wire 452, contact 453 of relay D^{154} , wire 454, contact D^{378} , wire 900, contact 901 of relay D^{379} , wire 902, contact 903 of relay D^{380} , wire 904, contact 905 of relay D^{381} , wire 906, contact 907 of relay D^{382} , wire 908, contact 909 of relay D^{383} , wire 910, contact 911 of relay D^{384} , wire 912, contact 913 of relay D^{385} , wire 914, contact 915 of relay D^{386} , wire 916, contact 917 of relay D^{387} , wire 918, contact 919 of relay D^{388} , wire 920, contact 921 of relay D^{389} , wire 922,

contact 163 of relay T^9 , wire 164, contact 165 of relay T^{10} , wire 166, wire 167, contact 168 of relay A^5 , wire 169, contact 170 of track relay T^{11} , wire 171, pole-changer P^5 , 5 and wire 30 to battery B^5 . This circuit is provided with a branch around contact 168 of relay A^5 , which branch passes from wire 166, through 172, contact 173 of relay X^5 , and wire 174 to wire 169.

10 Inasmuch as relay A^3 is thus normally controlled by relay A^5 , and relay A^5 is controlled up to point 18, it follows that when relay X^5 is open, signal S^3 and ramp R^3 are likewise controlled up to point 18. This, 15 then, is the control limit of these devices during passage of a westbound train. An eastbound train, however, closes relay X^5 as it passes signal S^5 , so that during a movement in this direction signal S^3 and ramp 20 R^3 are controlled only up to point 13. These control limits are more clearly indicated in Fig. 5.

The control of the signals and ramps governing westbound trains is identical to the 25 control of the eastbound signals and ramps hereinbefore explained. That is, signal S^{16} and ramp R^{16} are controlled in the same manner as signal S^5 and ramp R^5 , and the same thing is true of signal S^8 and ramp R^8 . 30 Signal S^{14} and ramp R^{14} are controlled in the same manner as signal S^7 and ramp R^7 , except that the first track section in the rear of S^{14} is included in the normal control of S^7 , whereas a corresponding section in the 35 rear of S^7 is not included in the control of S^{14} . Signal S^{12} and ramp R^{12} are controlled in the same manner as signal S^7 and ramp R^7 or signal S^9 and ramp R^9 . Signal S^{10} and ramp R^{10} are controlled in the same 40 manner as signal S^3 and ramp R^3 .

Before explaining the operation of the system as a whole, it should be pointed out that the distance between each two adjacent pairs of ramps is at least equal to the maximum braking distance for all cars or trains. 45

The operation is as follows:

Assuming that an eastbound car or train enters track section 4-5, it is, of course, apparent that this train has already placed 50 signals S^2 , S^4 and S^6 in the stop position, and that the ramps corresponding to these signals are kept in the de-energized condition. As the train enters section 5-6, the opening of track relay T^6 places signal S' at stop. No change in the condition of the apparatus occurs thereafter until the train passes signal S^3 , except that signal S^2 returns to the proceed position when the rear end of the train passes point 6. When the 60 train passes signal S^3 , the opening of track relay T^8 causes signal S^3 to move to the stop position, but signal S' is still held at stop, so that ramp rail R' is held in the de-energized condition. The opening of 65 track relay T^8 also causes signals S^8 and

S^{10} to move to the stop position, and so prevents ramp R^8 or ramp R^{10} from being energized by a westbound train. As the train passes signal S^5 , this signal goes to stop and the circuit for relay A' closes. 70 Signal S^3 is still in the stop position, however, so that relay A' is energized in the reverse direction whereby signal S' moves only to the caution position. As the train passes signal S^6 this signal returns to the 75 proceed position, and as the train passes point 13, the relay A^3 which controls signal S^3 , becomes energized. Signal S^3 moves only to the caution position, however, because signal S^5 is at stop, but this movement of signal S^3 reverses pole-changer P^3 , 80 so that signal S' moves to the proceed position. The entrance of the train into section 13-14 opens the circuit for relay A^{12} , so that signal S^{12} moves to the stop position, and the subsequent entrance of the train into section 14-15 opens the circuit for relay A^{14} , so that signal S^{14} moves to the stop position. Signal S^7 is, of course, 85 placed at stop as it is passed by the train, and as the train passes point 15, signal S^8 returns to the proceed position. No further change occurs until the train passes point 17, whereupon signal S^9 is placed at stop. When the train passes point 18 the circuit 90 for relay A^5 becomes closed, but signal S^7 being at stop, signal S^5 moves only to the caution position. Signal S^3 returns to proceed, however, as also does signal S^{10} . When the train reaches point 20, the circuit for 95 relay A^7 becomes closed, but signal S^7 moves only to the caution position, because signal S^9 is at stop. Signal S^{11} , of course, moves to the stop position when the train reaches this point, and signal S^{16} is placed at stop. 100

At point 21, signal S^{12} returns to the proceed position at point 23, signal S^9 returns to the caution position and signal S^8 moves to the stop position. At point 24, signal 105 S^{14} returns to the proceed position, and at point 26 signal S^{15} moves to the stop position. Signal S^{16} , of course, returns to the proceed position as the train passes point 27.

The operation of the system during the movement of a westbound train will be 110 understood from the foregoing without detailed explanation.

I will now assume that an eastbound train occupies track section 9-10. This train holds signal S' in the stop position, and 115 prevents ramp R' from being energized. If a following eastbound train, then, should pass signal S' it would incur a brake application at ramp R' which is more than the maximum braking distance in the rear of 120 the first train. This train is absolutely protected, therefore, from a rear-end collision. I will now assume that an eastbound train 125 passes S^7 at full speed at the same time that a westbound train passes signal S^{12} also at 130

full speed. The eastbound train prevents ramp R^{12} from becoming energized and the westbound train prevents ramp R^7 from becoming energized, so that the two trains will incur brake applications at these two ramps. Since these ramps are separated by at least double maximum braking distance, it follows that both trains will come to a stop before colliding. The same thing is true when trains moving towards each other pass signals S^4 and S^6 at the same time, and likewise when trains moving toward each other pass signals S^9 and S^{14} at the same time. If two trains approaching each other pass signals S^3 and S^8 at the same time, the eastbound train will receive a brake application at ramp R^3 , and the westbound train will receive a brake application at ramp R^8 because signal S^8 is placed at stop by the entrance of the eastbound train into section 8-9. Both trains will, then, be brought to a stop before they can collide. The same condition exists when trains approaching each other pass signals S^5 and S^{10} at the same time, signals S^7 and S^{12} at the same time, and signals S^{11} and S^{16} at the same time.

Although I have herein shown and described only one form of trackway apparatus embodying my invention, it is understood that various changes and modifications may be made therein within the scope of the appended claims without departing from the spirit and scope of my invention.

Having thus described my invention, what I claim is:

1. In combination, a stretch of railway track over which traffic moves in both directions, two signals governing movements in opposite directions along said track and separated by at least double maximum braking distance, train-controlled means including track circuits for placing both of said signals at stop when a train enters the portion of track between said signals and for holding the signal at the exit end at stop until the train leaves said portion, means for permitting the other signal to return to a proceed indication when the train has passed a point between said signals, a train controlling ramp adjacent each signal, and means for preventing energization of each ramp when the adjacent signal indicates stop.
  2. In combination, a stretch of railway track over which traffic moves in both directions, two train-controlling ramps separated by at least double maximum braking distance, train controlled means including track
- circuit for preventing either of said ramps from becoming energized after a train enters the portion of track between said ramps and for keeping the ramp at the exit end de-energized until the train leaves such portion, a stick relay for each ramp, means controlled by a train entering said portion of track for energizing the stick relay for the ramp at the entering end and for keeping it energized until the train has passed such ramp, and means for permitting the ramp at the entering end of said portion of track to become energized when a train has passed a given point between said ramps.
3. In combination, a stretch of railway track over which traffic moves in both directions, a plurality of pairs of train-controlling ramps located along said track at intervals at least equal to maximum braking distance, the two ramps of each pair being arranged for co-operation with trains moving in opposite directions, respectively, means controlled by a train moving in either direction for preventing energization of each co-operating ramp immediately after it passes such ramp, and for preventing energization of at least two opposing ramps in advance of the train, and means controlled by a train after passing each pair of ramps for permitting energization of the co-operating ramp of the pair next in the rear.
4. In combination, two successive blocks of a railway track, a train-controlling ramp for each block for co-operation with a train moving in one direction, a line relay for each ramp, track circuits for the blocks, means for controlling the line relay for the forward block by the track circuits for such block, means for controlling the line relay for the rear block by the track circuits for such block and by the line relay for the forward block, a stick relay for removing the line relay for the rear block from control by the line relay for the forward block, and means controlled by a train passing through said blocks in said direction for closing said stick relay and holding it closed at least until the train leaves the forward block, said last-mentioned means being ineffective to close said stick relay when a train passes through said blocks in the opposite direction.

In testimony whereof I affix my signature in presence of two witnesses.

RONALD A. McCANN.
